(57) **CLAIM**

The ornamental design for an automobile body, as shown and described.

DESCRIPTION

FIG. 1 is a front perspective view of an automobile body showing our new design.

FIG. 2 is a rear perspective view thereof.

FIG. 3 is a front view thereof; and,

FIG. 4 is a fragmentary rear view thereof.

It will be understood that the top is plain and unornamental and further that the broken line shown throughout the drawings is for illustration only, forming no part of the claimed design.
